CLAIM

The ornamental design for a cymbal, as shown and described.

DESCRIPTION

FIG. 1 is a perspective view showing the front, left and right sides, and the top of the cymbal according to a first embodiment of my new design;

FIG. 2 is a perspective view showing the back, left and right sides, and the top thereof;

FIG. 3 is a front view thereof;

FIG. 4 is a top view thereof;

(Continued)

FIG. 5 is a perspective view showing the front, left and right sides, and the top of the cymbal according to a second embodiment of my new design;

FIG. 6 is a perspective view showing the back, left and right sides, and the top thereof;

FIG. 7 is a front view thereof; and,

FIG. 8 is a top view thereof.

The broken lines represent the portions of the cymbal that form no part of the claimed design.
